VALVE CONSTRUCTION

Carroll M. Breed, Ypsilanti, Mich.

Application July 29, 1946, Serial No. 687,035

2 Claims. (Cl. 251—43)

1

This invention relates generally to oil burners and refers more particularly to an improved valve assembly for oil burners.

The usual oil burner comprises an annular fuel reservoir, and a source of fuel supply in the form of a container or conduit. The flow of fuel from the container to the reservoir is ordinarily controlled by a valve assembly having a manually operable valve member. The specific construction of the control valve may vary with different makes of burners, but in practically all instances, the several parts thereof are formed of brass or some equivalent rust-resisting material.

While valve assemblies of the above general type afford satisfactory service notwithstanding moisture conditions, nevertheless, they are very costly to produce and it is an object of this invention to substantially reduce the cost of manufacture while maintaining at least the equivalent high standard of service by providing a valve assembly wherein only the essential parts are formed of rust-resisting materials, such for example, as brass.

Another object of this invention is to provide a valve assembly wherein the several parts thereof may be easily produced by high production methods with a minimum amount of equipment and may also be readily assembled.

The foregoing as well as other objects will be made more apparent as this description proceeds, especially when considered in connection with the accompanying drawings, wherein:

Figure 1 is a semi-diagrammatic elevational view, partly in section, of an oil burner having a valve assembly constructed in accordance with this invention; and

Figure 2 is a view similar to Figure 1 showing a modified form of construction.

As will be understood from the following description and the appended claims the present invention concerns itself particularly with the valve assembly for controlling communication between a source of fuel oil supply and a reservoir of an oil burner. The valve assembly may be advantageously used in connection with any one of numerous different designs of oil burners, and the present invention is not restricted to any one specific design. However, for the purpose of illustration, the oil burner shown in Figure 1 of the drawings comprises the usual inner and outer perforated tubes 10, a lighting ring 11 and an annular reservoir 12 for receiving the lighting ring 11. The reservoir 12 is adapted to receive fuel oil from a container 13 welded or otherwise suitably secured to the bottom of the reservoir and

2

communicating with the latter through a valve assembly 14.

The valve assembly comprises a housing in the form of an elongated tube 15, an insert 16 and a valve member 17. In the interests of economy, the tube 15 is preferably made of steel and is supported in an inclined position. The length of the tube 15 and the angle of inclination is so determined that the upper end of the tube projects a substantial distance above the top of the reservoir 12. As a result, escape of fuel oil from the reservoir through the open upper end of the tube 15 is avoided without the necessity of providing packing glands or equivalent expensive sealing means. As shown in Figure 1 of the drawing, the lower end of the tube is secured to the base of the reservoir and is provided with an opening 18 registering with an opening in the base of the reservoir to enable fuel oil to flow from the tube into the reservoir.

The insert 16 is sleeved into the lower end portion of the tube 15 and has a pressed fit with the latter. If desired the insert may be fused, soldered or otherwise fixedly secured in the tube to form an integral construction. In any case, the lower end of the insert projects through an opening 20 formed in one side of the supply container 13 far enough to allow the end of the tube 15 to rest on the supply container, and then the tube 15 and supply container 13 and insert 16 are all fused together. A bore 21 is formed through the insert and a port or opening 22 is formed in the side wall of the insert intermediate the ends thereof in a position to register with the opening 18. Thus a fluid connection is provided between the supply container 13 and the interior of the reservoir 12.

It will also be noted from Figure 1 of the drawing that the outer end portion of the bore is enlarged to provide an annular frusto-conically shaped valve seat 23 located between the opening 22 and the supply container 13. The flow of fuel oil from the supply container 13 to the reservoir 12 is controlled by the valve member 17 having a stem 24 projecting into the tube 15 through the open upper end of the latter and terminating at the lower end in a reduced portion 25. The reduced portion 25 projects into the bore 21 of the insert, and has a diameter less than the diameter of the bore to provide a passage around the same. The lower end of the reduced portion 25 is conically shaped to engage the seat 23 and close communication between the supply container 13 and the reservoir 12. In order to prevent rusting of the valve seat and

thereby seriously affecting proper operation of the burner, the insert 16 is formed of a rust-resistant material, such for example, as brass.

In the present instance, the valve stem 24 is threaded in the upper end of the bore 21 in the insert 16, and a handle or knob 26 is welded or otherwise fixed to the upper end of the valve stem to enable readily manipulating the valve. As indicated above, the upper end of the tube 15 projects above the reservoir 12 so that it is not necessary to provide expensive packing around the valve stem 24. Thus, it will be noted that the valve assembly is composed of a relatively few simple parts capable of being inexpensively manufactured, assembled and installed.

The embodiment of the invention shown in Figure 2 differs principally from the one previously described in that the valve assembly 27 projects horizontally from the outer side wall of the reservoir 12. The valve assembly 27 comprises an elongated tubular casing 28, a rust-resistant insert 29 and a valve member 30. The tubular casing 28 is preferably made of steel and the insert 29 is sleeved within the inner end of the casing 28. The inner end of the insert projects beyond the corresponding end of the tubular casing, and is provided with an internally threaded recess 31 for receiving a plug 32. The plug 32 extends into an opening formed in the outer side wall of the reservoir 12 and is welded or otherwise suitably secured to the latter wall.

As shown particularly in Figure 2 of the drawings, the plug 32 and the insert are provided with aligned passages 33. The passage 33 through the insert 29 is enlarged as at 34 to provide a frusto-conically shaped seat 35 and an opening 36 is formed through the side wall of the insert outwardly beyond the seat 35.

A plug 37 extends through the tubular casing 28 into the opening 36 and is welded or otherwise secured to the tubular casing 28. The plug 37 is formed with a bore 38 and is threaded at the outer end for attachment to one end of a conduit 39. The opposite end of a conduit 39 has a fitting 40, and the latter is secured to one side of the supply container 13. The above arrangement provides a fluid connection between the supply container 13 and the enlarged portion 34 of the passage 33 in the insert at a point spaced outwardly from the valve seat 35. The flow of fuel oil through the passage 33 to the reservoir 12 is controlled by a valve member 41 having a valve stem threaded in the outer end of the enlarged portion 34 of the passage 33 and having a reduced portion 42 for engaging the valve seat 35. The valve member 41 projects through the outer end of the tubular casing 28, and a knob 43 is secured thereto to enable convenient manipulation of the valve member.

Inasmuch as the outer end of the tubular casing 28 does not project above the reservoir 12, it is necessary to provide a seal 44 around the valve member in order to prevent the escape of fuel oil. The seal 44 comprises a collar 45 seated in the outer end of the tubular casing

28 against an annular shoulder 46 and having a frusto-conically shaped seat 47 at the outer side thereof. The seat 47 is engaged by a packing material 48 surrounding the valve member and held in sealing engagement with the latter by a packing nut 49. The packing nut 49 is threaded on the outer end portion of the tubular casing and may be adjusted to assure a tight seal around the valve member.

In the embodiment of the invention shown in Figure 2, it is preferred to form the insert 29, collar 45 and packing nut 49 of a rust-resistant material, such for example, as brass. The remaining parts, however, may be formed from a less expensive material without seriously impairing the life and successful operation of the valve assembly.

What I claim as my invention is:

1. A regulating valve assembly for oil burners, comprising a supply container having an opening through one wall, a steel tube having an opening through one side intermediate the ends thereof and positioned with the inner end abutting said wall of the container around the opening through said wall, an insert of rust resisting material secured within the inner end portion of the tube and having an axially extending bore therethrough enlarged at the outer end of the insert to provide an annular valve seat intermediate the ends of the bore, a port through one side of the insert connecting the enlarged portion of the bore with the opening in said tube, said insert having the inner end projecting inwardly beyond the adjacent end of the tube into the opening in said supply container and having the outer end projecting beyond the opening in said tube whereby fluid passes solely through the bore in the insert between the supply container and the opening in said tube, a valve member having a stem projecting into the tube through the outer end thereof and threaded into the enlarged portion of the bore in the insert, and a reduced part on the inner end of the valve stem engageable with the valve seat.

2. The regulating valve assembly defined in claim 1 wherein the inner end of the tube is permanently secured to the container to form a unit with the latter.
